CLAIM

The ornamental design for a multi-functional scissor, as shown and described.

DESCRIPTION

FIG. 1 is a front, right side, top perspective view of a multi-functional scissor showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, right side, top perspective view of a multi-functional scissor wherein the blades of the multi-functional scissor are covered by a case.

The broken lines depict portions of the multi-functional scissor that form no part of the claimed design.
